UNITED STATES PATENT OFFICE.

CLINTON CLARENCE HUMPHRIES, OF NORFOLK, VIRGINIA.

DEVICE FOR MOISTENING AND WRINGING COMPRESSES.

1,397,423.

Specification of Letters Patent.

Patented Nov. 15, 1921.

Application filed March 8, 1921. Serial No. 450,608.

To all whom it may concern:

Be it known that I, CLINTON C. HUMPHRIES, a citizen of the United States, residing at Norfolk, in the county of Norfolk and 5 State of Virginia, have invented certain new and useful Improvements in Devices for Moistening and Wringing Compresses, of which the following is a specification.

This invention relates to devices for moistening and wringing compresses.

There has long been a need for a device which will moisten and wring compresses, particularly hot compresses, such as are used in hospitals and by barbers and others.

15 The invention provides a combined moistening and wringing device which meets sanitary requirements and which avoids manual wringing and undue handling of the compress by the operator. In its broadest 20 aspect the device comprises some form of wringer and some form of moistening device so correlated that they may be caused to act successively upon the compress without manual contact with the compress. I 25 prefer an arrangement in which the heated liquid, usually water, acts also upon the wringing device to heat the latter to, or approximately to, the temperature of the heated compress so that the wringer does 30 not abstract heat from the latter during the wringing operation.

Various specifically different wringing devices may be used but I prefer a wringer of the press type in which the heated liquid 35 is projected upon the compress while the latter is in the press prior to the pressing or wringing operation. A convenient way of securing this result is to provide one 40 press head with a water spraying or distributing device, and the other press head with a drain connection. I illustrate this embodiment of the invention in the accompanying drawing in which,—

Figure 1 is a vertical section of the complete device, viewed from the front.

Fig. 2 is a section on the line 2—2 of Fig. 1.

Fig. 3 is a section on the line 3—3 of Fig. 2.

50 Fig. 4 is a perspective view of a portion of the lower press head, and

Fig. 5 is a perspective view of the upper press head.

In the drawing, 11 presents a hollow 55 pedestal upon which is mounted a frame or yoke 12 whose general form is clearly shown

in the drawing. Mounted on the yoke 12 is a recessed casting 13 formed with a peripheral flange 14 and the internal bracing or staying webs 15. A perforated plate 16 is mounted on the lower face of the recessed casting 13 with its periphery secured in any suitable manner to the flanges 14. The webs 15 offer support to the central portions of the plate 16 to assist it in withstanding the stress exerted upon it by the pressing operations.

The plate 16 may be made of any suitable foraminous material but I believe that a perforated plate is preferable to other materials, such, for example, as a heavy woven wire screen which obviously may be made to serve a similar purpose.

Casting 13 is mounted on the yoke 12 by brackets 17 which are offset as shown for a purpose which I shall describe hereafter.

The lower press head comprises a recessed casting 18 which is guided in a vertical direction partly by lugs 19 which embrace the vertical portions of the yoke 12, and partly by a drain tube 20 which slides within a drain pipe 21 fixed in the middle portion of the yoke 12 and extending down within the pedestal 11. Drain pipe 21 is provided with a trap 22 housed within the pedestal 11 and connected to any suitable water discharge pipe (not shown).

The recessed casting 18 is formed with a plurality of transverse bearer bars 23 upon which rests a removable perforated plate 24. Any suitable foraminous material might be substituted for the perforated plate illustrated. I prefer to make the element 24 removable to permit cleaning of the interior of the recessed casting 18. Casting 18 is provided with an upward extending flaring flange 25 which projects above the plate 24 and serves to catch all the liquid used in the device and insure its discharge through the plate 24 to the drain pipe 20. The offsets in the bracket 17 are to give clearance to this flange 25.

Pivotedly connected at 26 to the casting 18 are two strut links 27 whose lower ends are pivoted at 28 to parallel arms 29, fixed to a rock shaft 30 which turns in bearings 31 in the pedestal 11. A foot lever or treadle 32 is rigidly connected to the shaft 30 and the parts are so arranged that depression of the foot lever 32 serves to elevate the casting 18. It will be observed that at the upward limit of motion of the foot lever 32 the arms

29 and the thrust links 27 approach alignment so that the casting 18 is lifted with considerable force. A water connection 33 controlled by a faucet 34 leads to the interior 5 of the casting 13 above the plate 16.

In the ordinary operation of the device the compress, which may be, for example, a folded towel, is laid upon the plate 24. The treadle 32 is then depressed to bring the 10 compress nearly or quite into contact with the plate 16. The faucet 34 is then turned on admitting water above the plate 16. This water flows downward through the perforations of the plate thoroughly saturating the 15 compress and incidentally heats plates 16 and 24 to approximately the same temperature as the compress. When this saturating and heating operation is completed the faucet 34 is turned off and casting 13 is allowed to drain. Further depression of the 20 treadle 32 then subjects the compress to sufficient pressure to expel the surplus water. Treadle 32 is then allowed to rise and the resulting descent of casting 18 and plate 24 25 give access to the compress which is removed from the press in condition for use.

It is desirable that the compress be somewhat smaller than the superficial area of the plate 24, and this plate and the plate 16 are 30 both provided with perforations extending close to their edges. These details are important as they insure that all the expressed water will have a free path to drain away. Otherwise there would be a tendency for the 35 expressed water to rise through the apertures in plate 16 and flow back into the compress as soon as pressure was relieved.

While I prefer the structure described as 40 a simple and satisfactory embodiment of the invention I am aware that other wringing devices might be used to produce a similar result and that the parts may be arranged in 45 specifically different ways to meet different conditions. I contemplate such variations of the structure and do not limit myself to the specific structure illustrated and described except to the extent specified in the claims.

What is claimed is:—

50 1. A device for preparing hot compresses, comprising in combination, a wringing device; means for delivering heated liquid

thereto and to a compress held thereby; and means for operating said wringing device to expel a portion of said liquid from said 55 compress.

2. A device for preparing hot compresses, comprising in combination, a liquid expressing press adapted to receive and support a compress; means for delivering a heated 60 liquid to the press and to the compress, whereby both are heated; and means for operating said liquid delivering means and said press.

3. The combination of a water spraying 65 device; a water expressing device; and means for causing each of said devices to act on a compress without intervening manipulation of the compress.

4. The combination of a water spraying 70 device; a water expressing device; a drain structure serving to receive water flowing from both devices; and means for causing each of said devices to act on a compress 75 without intervening manipulation of the compress.

5. The combination of a water spraying device; a support serving to position a compress in the path of water discharged by said spraying device; and means operable to express water from said compress while the latter is positioned by said support.

6. The combination of a water spraying device; a drain; a support serving to position a compress over said drain and in the 85 path of water discharged by said spraying device; and means operable to express water from said compress while the latter is positioned by said support.

7. The combination of a press adapted to 90 receive a compress; a spraying device operable to wet a compress while in said press; means for operating said press; and means for conducting away the off-flowing water.

8. A device for preparing wet compresses, 95 comprising in combination two opposed pressing heads; a liquid-delivering means associated with one head; a liquid-draining means associated with the other head; and means for operating said pressing heads.

In testimony whereof I have signed my name to this specification.

CLINTON CLARENCE HUMPHRIES.
